UNITED STATES PATENT OFFICE.

ALBERT SUEHY, JR., AND ERNEST W. HOPPER, OF PHILADELPHIA, PENNSYLVANIA.

MACHINE FOR MAKING PERFORATED MUSIC ROLLS.

1,427,336.

Specification of Letters Patent. Patented Aug. 29, 1922.

Application filed January 6, 1921. Serial No. 435,405.

To all whom it may concern:

Be it known that we, ALBERT SUEHY, Jr., and ERNEST W. HOPPER, citizens of the United States, residing at Philadelphia, county of Philadelphia, and State of Pennsylvania, have invented a new and useful Improvement in Machines for Making Perforated Music Rolls, of which the following is a full, clear, and exact description, reference being had to the accompanying drawings, which form a part of this specification.

Our invention relates to mechanism for perforating music rolls for use in connection with player pianos.

The object of our invention is to provide a hand operated machine which will be simple in construction and operation and which will enable persons with only a slight knowledge of music to readily produce music roll records from sheet music.

A further object of our invention is to provide a machine which will be accurate and so constructed as to permit the operator to vary the record in order to give his own interpretation to the selection recorded.

A further object of our invention is to provide a machine so constructed as to enable one skilled in music to compose and record simultaneously.

We will now describe our invention in detail with reference to the accompanying drawings, in which—

Fig. 1 is a plan view of a machine embodying our invention, partly broken away for clearness.

Fig. 2 is a side elevation of the machine.

Fig. 3 is a cross-sectional view of the machine.

Fig. 4 is a sectional view on line 4—4, Figure 3.

Fig. 5 is a sectional detail of the take-up roller drive.

Upon a base *a* is mounted a frame *b* which carries the perforating mechanism and rolls and feed mechanism for the paper. Secured to the frame is a support *c* upon which is supported a scale plate *d*, of celluloid or other material, upon which is printed a facsimile of a piano keyboard, each key having its respective note symbol marked thereon, and a scale as shown in Figures 1 and 4. A second scale plate *d'* bearing a facsimile of a piano keyboard in line with scale *d* is positioned in front of the punches *g*. In front of the scale plate sup-

port and extending transversely of the frame is a plate *e* provided with a series of holes *f* adapted to act as a die for a series of punches *g*, adapted to punch a hole in the paper of a size corresponding to a sixtieth part of a note, having enlarged heads and loosely carried by a transversely extending punch retracting bar *h*, supported at both of its ends by means of springs *i* carried on guides *j*. The bar *h* has a lug *n* at each of the ends for depressing the bar. The punches are guided with respect to the die plate by means of a guide plate and stripper *k*. A pressure bar *l* is carried by arms *m* pivoted on the frame, and a bar *o* having an upturned extension *p*, the upper end of which is faced with leather, extends between the arms *m* at a point above the punches. A series of selectors *q* having hooked tails *r* are rotatably mounted on a shaft *s* extending between arms *m*, the selectors being so proportioned that their upper ends will normally rest on the leather faced edge of the extension *p*, the leather facing acting as a bumper. An individual selector is provided for each of the black and white keys of the piano keyboard illustrated on the scale plate, for the sustaining pedal and for any automatic control devices. The selectors are provided with extensions 30 permitting their manual movement into and out of operative position, the extensions of those selectors corresponding to the black keys and those corresponding to the white keys of the piano keyboard being of different lengths respectively, whereby they are differentiated. The extensions are provided on their upper surfaces with projections 31, which serve as grips for the fingers when the selectors are manipulated. A punch is provided beneath each selector. The punches are adapted to be operated by the pressure bar *l* through bar *o*, operative connection being formed between the punch heads and bar *o* by the tails *r* on the selectors, which when the selectors are pulled out engage under bar *o* and form gags, as shown in dotted lines in Figure 3. The retractor bar *h* is depressed by engagement of bar *o* with lugs *n*. It will thus be seen that if any selector or series of selectors are pulled out and the pressure bar depressed, the punches beneath the selector pulled will be operated. On the release of the pressure bar, the punches are returned to normal by the retractor bar under the influence of its springs.

A pan is positioned beneath the punch to collect the punchings.

The paper holding and feeding mechanism comprises a blank paper roller *t* carried by the frame at a point behind the punches and a take-up roller *u* carried by the frame in front of the punches to receive the perforated paper. The paper is led from the roller *t* under the punches between 5 the guide plate *k* and the die plate *e*, thence over a feed roller *v*, mounted on a shaft *w*, one end of which is provided with a turn button *x*, to the take-up roller *u*, which is provided with a hook, seated in 10 a recess, to receive the end of the paper. The paper is guided to the feed roller by strips 19 and by flanges on the take-up roller *u*. Tension is maintained on the paper by means of a series of rollers *y*, carried by levers *z* journaled on a shaft 2 15 and tensioned by springs 3 which press on the paper as it passes over the roller *v*. The rollers may be lifted from the roller *v* by turning shaft 16 which is provided with 20 flat surfaces as indicated in Fig. 3.

The shaft *w* is provided at one end with a pulley 4 adapted to be driven by a ratchet wheel 5 mounted on the other end of shaft *w*, through a belt 6 and a pulley 7 frictionally secured to take-up roller *u* by a split 25 sleeve 27.

The ratchet wheel is driven by a pawl 9 provided with a cam surface 10, pivoted to an arm 11 pivotally mounted on shaft *w*. 30 A spring 12 secured to the pawl and to the arm 11 tends to maintain the pawl in engagement with the ratchet teeth.

The pawl is pivotally connected to one end of a link 13, the other end of which is 35 pivoted to a spring-tensioned arm 14 integral with one of the pressure bar arms *m* and forming a bell crank therewith, so that the pawl may be actuated by the pressure bar. The arm 14 extends through an aperture in the frame, the faces of which are provided with rubber bumpers 15. A spring-tensioned stop 28 is positioned adjacent the arm 14, which may be moved into and out of the path of the arm, so 40 that when desired the movement of the pressure bar *l* may be limited to that required to actuate the pawl without actuating such punches as may be operatively connected by their selectors.

45 A spring-tensioned lever 17 pivoted at one end on shaft 2 is provided at its free end with a roller 8 adapted to engage between the teeth of the ratchet wheel and act as a detent or spacer. The roller 8 50 also acts to hold the pawl 9 out of engagement with the ratchet on the return movement of the pressure bar, as shown in Fig. 3, so that the ratchet wheel may be backed manually if desired.

55 A second lever 20 is pivoted at one end

to shaft 2 adjacent to lever 17 and extends downward to the cam surface 10 in pawl 9. A roller 21 mounted on its free end is adapted to contact with the cam surface in the active movement of the pawl and force 70 the pawl away from the ratchet. An adjusting cam having three faces 22, 23 and 24 is mounted to position lever 20 against the action of a spring to fix the distance the pawl may advance the ratchet wheel before 75 it is released by the action of cam surface 10. The faces 22 and 23 so position the lever as to effect the release of the pawl when the pawl has advanced the ratchet wheel one and two teeth respectively. The 80 face 24 is adapted to so position the lever as to maintain the pawl out of action and a stop 26 is positioned on the lever 20 so that when the lever is positioned by face 24 the lever 17 and the spacing roller carried thereby will be thrown out of action and the ratchet wheel will be free to be moved a fraction of a tooth, by hand.

We will now describe the operation of the machine to effect the record of a selection. A roll of blank paper corresponding to roller *t* is inserted and the free end led under the punches over roller *v* and secured to the hook on roller *u*. The tension rollers *y* are lowered onto the paper. The sheet 95 music to be recorded is studied and the selector corresponding to the piano key which would be struck for the first note is pulled down. The adjusting cam is then set to permit the pawl to move the ratchet wheel 100 two teeth, which has the effect of rotating the feed roller *v* and advancing the paper a distance corresponding to the movement of the ratchet wheel. The pressure bar is now depressed and its initial movement causes 105 the pawl to be advanced through the action of arm 14 on link 13, then rotating the ratchet wheel and roller *v* and advancing the paper. When the pawl has rotated the ratchet wheel a distance of two teeth, it is 110 disengaged by cam surface 10. Further depression of the pressure bar causes the punch corresponding to the selector pulled down to be depressed, through the connection formed by the tail of the selector, and 115 the paper is perforated. If, for example, the first note is a quarter note, the pressure bar is depressed sixteen times, the paper advances between each perforation and the perforations are evenly spaced. At the 120 point where the next note of the selection comes in the selector corresponding to the piano key which would be struck to play it is pulled down, and so on. As each note is completed, the selector corresponding to 125 it is raised and as new notes come in, the selectors corresponding to them are pulled down.

If now the sheet music calls for a "run." After the first perforation of the first note 130

of the run is made, the adjusting cam is turned so that the lever 20 is positioned by the face 23 and the pawl will be thrown out after rotating the ratchet one tooth.

5 The succeeding notes are brought in by pulling down their corresponding selectors, successively. The spacing between notes is now half that under ordinary circumstances and the perforations of the same note instead of 10 being spaced are lapped as indicated at 25 in Fig. 1, where a portion of a music roll is shown. Thus, the rapid slurred effect of the notes in a run is obtained.

The single tooth advance of the feed is 15 also used when fast time is desired, although it is impractical where the same note is repeated, as it is obvious that no spacing would occur between a note and its repetition, with the result that the repeated note 20 would be recorded as a part of the original note.

If now the selection requires a chord to be struck, it is undesirable that all the notes 25 of the chord be begun exactly simultaneously since if they are, a mechanical effect is produced, while in reality a performer never does and in fact cannot strike all the notes at exactly the same time. To produce 30 a natural effect, the adjusting cam is turned so that face 24 will position lever 20 so as to prevent the pawl from advancing the ratchet, and lever 17 will be displaced by stop 26 to free the ratchet wheel. The selector corresponding to the first note of the 35 chord is then pulled down and a perforation made. The feed is then turned by hand less than one tooth and the selector corresponding to the second note is pulled down and a perforation made, the feed 40 again turned, and so on until all the notes of the chord are started. The adjusting cam is then again turned to adjust the feed to two teeth and the notes of the chord completed.

45 If, at any time, it is necessary to repeat a note, it is obvious that an extra space must be interposed between the last perforation of the original note and the first perforation of the repeat. To effect this, the 50 transversely movable stop is moved out into the path of the arm 14 and the pressure bar depressed. The initial movement effects a movement of the feed, but the movement is stopped by arm 14 contacting with stop 55 28 and no perforation is made. The pressure bar is returned to normal and the stop pushed out of the path of arm 14. The pressure bar is again depressed and its preliminary movement effects a second advance 60 of the feed before the perforation is made. It will be obvious that by the use of stop 28, two advances of the feed are effected before a perforation is made and that the last perforation of the original note is separated 65 from the first perforation of the re-

peat by twice the space separating perforations of the same note, thus permitting a release of the original note.

Having now fully described our invention, what we claim and desire to protect by Letters Patent is:—

1. A machine for making perforated music rolls comprising a series of punches corresponding to the notes of a piano, punch actuating means, and a series of selectors 75 corresponding to the punches adapted to be positioned manually to effect an operative connection between the punches and the punch actuating means, those selectors corresponding to the black keys of the piano 80 keyboard and those corresponding to the white keys being differentiated from each other by differences in their length.

2. A machine for making perforated music rolls comprising a series of punches 85 corresponding to the notes of a piano, punch actuating means, and a series of selectors corresponding to the punches adapted to be positioned manually to effect an operative connection between the punches and the 90 punch actuating means, said selectors being provided on their upper surfaces with projections adapted to serve as grips for the fingers when said selectors are manipulated and those selectors corresponding to the 95 black keys of the piano keyboard being differentiated from those corresponding to the white keys by differences in their length.

3. A machine for making perforated music rolls comprising a plurality of 100 punches, a plurality of selectors adapted to be manually positioned to render said punches operative, punch actuating means, means adapted to hold a roll of blank paper, a take-up roll adapted to receive the perforated paper, a feed roll, and means actuated by the punch actuating means adapted to drive the feed roll and take-up roll intermittently.

4. A machine for making perforated 110 music rolls comprising a plurality of punches, a plurality of selectors adapted to be manually positioned to render said punches operative, punch actuating means, means adapted to hold a roll of blank paper, a take-up roll adapted to receive the perforated paper, a feed roll, means actuated by the punch actuating means adapted to drive the feed roll and take-up roll intermittently, and means tending to resist movement of the 120 feed roll.

5. A machine for making perforated music rolls comprising a plurality of punches, a plurality of selectors adapted to render said punches operative and inoperative, a blank roll holder, a feed roller, a take-up roller driven from said feed roller, a ratchet wheel in driving relation with said feed roller, a pawl, adapted to drive said ratchet wheel, operatively connected with 130

said punch actuating means, adjustable means adapted to release said pawl from the ratchet wheel after movement of said ratchet wheel, and a detent engaging said ratchet wheel and tending to resist movement thereof.

6. A machine for making perforated music rolls comprising a plurality of punches, a plurality of selectors adapted to render said punches operative and inoperative, a blank roll holder, a feed roller, a take-up roller driven from said feed roller, a ratchet wheel in driving relation with said feed roller, a pawl, adapted to drive said ratchet wheel, operatively connected with said punch actuating means, and adjustable means adapted to release said pawl from the ratchet wheel after a predetermined movement of said ratchet wheel.

7. A machine for making perforated music rolls comprising a plurality of punches, a plurality of selectors adapted to be positioned to render said punches operative, punch operating means, a blank paper roll, a driven feed roll, a take-up roll driven from said feed roll, means actuated by said punch operating means to drive the feed roll, and means adapted to interrupt the feed roll drive after movement of the feed roll.

8. A machine for making perforated music rolls comprising a plurality of punches, actuating means for said punches, a plurality of selectors, one for each punch, adapted to make and break operative connection between said punches and said actuating means, a blank paper carrier, a take-up roller, a feed roller, means to drive said feed roller, means forming a positive connection between said punch actuating means and said driving means, and means forming a frictional connection between said feed and said take-up rollers.

9. A machine for making perforated music rolls comprising a plurality of punches, a plurality of selectors adapted to render said punches operative and inoperative, a blank roll holder, a feed roller, a take-up roller frictionally driven from said feed roller, a ratchet wheel in driving relation with said feed roller, a pawl, adapted to drive said ratchet wheel, operatively connected with said punch actuating means, and adjustable means adapted to release said pawl from the ratchet wheel after a predetermined movement of said ratchet wheel.

10. A machine for making perforated music rolls comprising a plurality of punches, a plurality of selectors adapted to render said punches operative, punch actuating means, means adapted to hold a blank roll of paper, a feed roll adapted to draw the paper beneath the punches, a take-up roll adapted to receive the perforated paper, means actuated by the punch actuating

means adapted to drive the feed roll intermittently, and means whereby said driving means may be rendered inoperative.

11. A machine for making perforated music rolls comprising a plurality of punches, a plurality of selectors adapted to be positioned to render said punches operative, punch operating means, a blank paper roll, a driven feed roll, a take-up roll frictionally driven from said feed roll, means actuated by said punch operating means to drive the feed roll, and means adapted to interrupt the feed roll drive after a predetermined movement of the feed roll.

12. A machine for making perforated music rolls comprising a plurality of punches, means to actuate the punches, a blank paper roll, a feed roll, a tension roll, a take-up roll, a ratchet wheel in driving relation with the feed roll, a detent yieldingly stopping said ratchet, a pawl adapted to actuate the ratchet wheel, said pawl being connected to and actuated by said punch actuating mechanism, means adapted to release said pawl after the ratchet wheel has been rotated a predetermined fraction of a revolution, and means to render said pawl and said detent inoperative and permit said ratchet wheel to be rotated manually.

13. A machine for making perforated music rolls comprising a plurality of punches, a plurality of selectors adapted to be positioned to render said punches operative or inoperative, punch operating means, a blank paper roll, a driven feed roll, a take-up roll, means operated by said punch operating means to drive said feed roll, means to interrupt said feed roll drive, and means adapted to position said interrupting means in a plurality of positions, each position effecting an interruption of said feed roll drive after a different predetermined movement of the feed roll.

14. A machine for making perforated music rolls comprising a plurality of punches, punch actuating mechanism, means adapted to hold a roll of blank paper, a feed roll adapted to draw the blank paper beneath the punches, tension rollers adjustable toward said feed roll to maintain a tension on the paper and away from said roll to permit paper to be freely passed over said roll, a take-up roll adapted to receive the perforated paper, and means actuated by the punch actuating mechanism adapted to drive the feed roll intermittently.

15. A machine for making perforated music rolls comprising a plurality of punches, punch actuating mechanism, a blank paper roller, a take-up roller, a feed roller, a ratchet wheel in driving relation with said feed roller, a pawl actuated by the punch actuating mechanism adapted to drive said ratchet wheel, and means adapted to normally hold said pawl free of said ratchet wheel.

and permit manual movement thereof, in either direction.

16. A machine for making perforated music rolls comprising a plurality of punches, 5 punch actuating mechanism, a blank paper roll, a take-up roll, a feed roll, means for driving the feed roll, said means being actuated to drive the feed roll in the preliminary movement of said punch actuating means, 10 and means adapted to stop the punch actuating means after actuation of the feed roll drive and before actuation of the punches.
17. A machine for making perforated music rolls comprising a plurality of punches, 15 a retractor bar, said punches being loosely carried by said bar, a guide bar provided
- with a plurality of guides, one for each punch, means adapted to be positioned to render the punches operative individually, punch actuating means adapted to actuate 20 those punches rendered operative, and means independent of said punch actuating means adapted to raise said retractor bar automatically and effect the retraction of said punches. 25

In testimony of which invention, we have hereunto set our hands, respectively, at Philadelphia, Penna., on the 4th day of January, 1921.

ALBERT SUEHY, JR.
ERNEST W. HOPPER.
